BRACE BUCKLE

Lowell W. Shields, Rochester, N. Y., assignor to
 The Hickok Manufacturing Company, Inc.,
 Rochester, N. Y., a corporation of New York

Application December 31, 1934, Serial No. 760,009

1 Claim. (Cl. 24—184)

The invention relates to buckles for braces or suspenders.

The object of the present invention is to improve the construction of that type of brace buckle comprising a frame or front and a clamping lever adapted to adjustably clamp the webbing of a shoulder strap between it and the frame or front.

More especially the invention has for its object to provide for brace buckles of this character a spring clamping lever designed to be used with various type styles or forms of frames or fronts and adapted to yield rearwardly in the direction away from the frame or front to adjust itself automatically to a wide range of webbings of different thicknesses and still hold the same in its adjusted position against accidental slipping when the shoulder strap to which the buckle is applied is subjected to the strains incident to the use of suspenders or braces.

Another object of the invention is to provide a resilient clamping lever adapted through its yielding characteristics to enable rigid bodies or fronts to be employed in the construction of brace buckles so that the fronts or frames of brace buckles may be made in the form of a solid ornamental front or frame, an open work frame which will ornamenteally expose portions of a webbing or a jeweled front which necessitates a more or less rigid structure and which should be relieved of any tendency to flex or bend it.

Another object of the invention is to provide a brace buckle adapted to avoid the careful adjustment required by old style solid buckle clamps to adapt the same for different web thicknesses.

Another object of the invention is to provide means for reinforcing the spring clamping lever adjacent the resilient portion thereof so that the metal will be sufficiently stiff and strong to prevent a rupture of the material and undue extension of the resilient portion.

With these and other objects in view, the invention consists in the construction and novel combination and arrangement of parts herein-after fully described, illustrated in the accompanying drawing and pointed out in the claim hereto appended, it being understood that various changes in the form, proportion and minor details of construction, within the scope of the claim, may be resorted to without departing from the spirit or sacrificing any of the advantages of the invention.

In the drawing:—

Fig. 1 is a front view of a brace buckle constructed in accordance with this invention and

shown applied to a portion of one of the shoulder straps.

Fig. 2 is a rear view of the same.

Fig. 3 is a central longitudinal sectional view through the brace buckle and a portion of the shoulder strap showing the spring clamping lever in its engaging position.

Fig. 4 is a similar view, the spring clamping lever being disengaged from the webbing to permit of adjustment of the same.

Fig. 5 is a transverse sectional view, the parts being arranged as shown in Fig. 1.

Fig. 6 is a detail perspective view of the buckle frame.

Fig. 7 is a detail perspective view of the spring clamping lever viewed from the back thereof.

Fig. 8 is a perspective view of the same looking at the front of the spring clamping lever.

Fig. 9 is a front view of a portion of a shoulder strap provided with a buckle having another design of buckle frame or front.

In the accompanying drawing in which is illustrated the preferred form of the invention the brace buckle comprises in its construction the buckle frame 1 and a spring clamping lever 2 constructed of sheet metal or other suitable material and consisting of a body portion 3 and a jaw 4 arranged at the top of the body portion and extending inwardly or forwardly therefrom substantially at right angles thereto. The spring clamping lever which may be stamped by suitable dies or otherwise formed is provided at the ends of the jaw 4 with laterally extending pivots 5 which are arranged in perforations 6 of ears 7 extending rearwardly from the ends of the front or frame 1. The pivotal connection between the spring clamping lever 2 and the frame or front 1 may be formed in any other suitable manner and it permits the jaw 4 to be swung into and out of engagement with webbing 8 or other suitable material of which the shoulder strap 9 may be constructed.

When the jaw 4 is in engagement with the webbing it is arranged in approximately a horizontal position depending upon the thickness of the webbing or other material of which the shoulder strap may be made and it is adapted to be swung downwardly out of such engagement from the position illustrated in Fig. 3 to that illustrated in Fig. 4. When the jaw is swung downwardly out of engagement with the webbing the latter may be adjusted in the usual manner to lengthen or shorten the braces. In order to enable the jaw to firmly and securely engage the webbing without liability of the latter slipping

and also without injuring the same the engaging edge of the jaw is provided at intervals with tapering relatively short spurs 10 formed by substantially segmental recesses 11.

- 5 The body portion 3 of the spring clamping lever extends downwardly from the jaw and is curved longitudinally of the webbing to present a convex inner or front face and a concave outer or rear face. The curvature of the body portion 10 of the clamping lever tends to cause the lower portion of the clamping lever to project rearwardly slightly and to facilitate the attachment of the adjustable end 12 of the webbing and the lower portion of the clamping lever is provided 15 with a transverse opening 13 forming a lower bar 14 which is arranged in a looped portion 15 of the end 12 of the webbing. The end 12 of the webbing is passed through the opening 13 and is stitched or otherwise secured to form the looped portion 15. The shoulder strap 9 is looped at the lower front portion in the usual manner to receive the connecting member 16 of the suspender ends 17.

25 In order to render the clamping lever resilient and permit the same to spring or yield rearwardly and automatically adjust itself to different thicknesses and qualities of webbing or other material employed in the manufacture of shoulder straps of suspenders or braces the said clamping lever 2 is provided at spaced points, approximately midway between the center and ends of the jaw with slits or cuts 18 formed by shearing or splitting the metal or otherwise. The slits or cuts 18 are disposed transversely of the jaw 4 and extend entirely across the same and have extensions 19 extending downwardly through a portion of the body of the lever. These slits or cuts form a resilient central portion 20 which produces a spring clamping lever and enables the 30 same to yield rearwardly away from the front or frame and automatically adjust itself to the thickness of a piece of webbing or other material and in order to reinforce the metal at the slits or cuts the lever is provided with embossing 40 21 forming ribs at the exterior of the spring clamping lever and grooves at the inner face of the same.

45 The reinforcing embossing are preferably of U-shape formation each embossing 21 being composed of spaced sides and a connecting portion. The embossing extends around the inner portions of the slits or cuts and may be of any desired length and any other form of reinforcing em-

bossing may of course be provided. A separate reinforcing embossing is provided at the inner portion of each slit and these embossings are located well within the side edges of the lever and they extend from the inner portions of the slits at opposite sides thereof and are arranged closely adjacent the said inner portions of the slits as clearly illustrated in Fig. 7 of the drawing. The slits render a portion of the jaw resilient and the reinforcing embossing stiffens the adjacent portions of the spring clamping lever. 10

15 The spring clamping lever is designed to be applied to various forms of buckle frames or fronts either solid as illustrated in Fig. 1 of the drawing or of open work as shown in Fig. 9. 15 The frame or front 22 illustrated in Fig. 9 is provided with ornamental openings 23 adapted to ornamenteally expose portions of the webbing 24. Various designs may of course be provided and the said spring clamping jaw will be found 20 particularly advantageous in buckles having jeweled fronts as it will enable the buckle frame or front to be made as rigid as desired without affecting the resilient action of the clamping 25 lever and the automatic adjustment of the brace 25 buckle to webbing and other material of different thicknesses. The resilient clamping lever also relieves the front or buckle frame of strain tending to flex the said frame or front so that there will be no liability of jeweled fronts being injured 30 when the buckle is opened and closed.

What is claimed is:—

35 A buckle of the class described comprising a buckle frame, and a clamping lever pivotally connected to the buckle frame and having a forwardly extending jaw movable toward and from the buckle frame, said lever being provided at spaced points between the ends of the jaw with transverse slits extending across the jaw and through the adjacent upper portion of the lever 40 and terminating at said upper portion of the lever to provide a resilient web engaging portion centrally of the jaw, said lever being also provided at the slits with separate approximately U-shaped embossings located well within the side 45 edges of the lever and extending from the inner portions of the slits at opposite sides thereof around the inner ends of the slits and arranged closely adjacent the same for reinforcing the lever adjacent the resilient web engaging portion without interfering with the resiliency of the 50 same.

LOWELL W. SHIELDS.
